UNITED STATES PATENT OFFICE.

PHILIP N. KNAPP, OF SOUTH NORWALK, CONNECTICUT.

STRAW-BRAID HAT.

1,219,111.

Specification of Letters Patent. Patented Mar. 13, 1917.

Application filed December 10, 1915. Serial No. 66,053.

To all whom it may concern:

Be it known that I, PHILIP N. KNAPP, a citizen of the United States, residing at South Norwalk, in the city of Norwalk, in the county of Fairfield and State of Connecticut, have invented a new Straw-Braid Hat, of which the following is a description.

My invention relates to straw-braid hats having a flexible brim; and the objects of my improvement are:

1st. To provide a flexible brim which will not open between the braids when bent down;

15 2nd. To provide a hat of flexible brim that will hold the shape better;

3rd. To accomplish the objects and realize the advantages of my improvement without enhancing the cost of the hat beyond commercial limits, and without discarding present machines on which straw-braid hats are sewed.

I attain these objects in the improved hat illustrated in the accompanying drawing, in which—

Figure 1 is a perspective view of the completed straw hat embodying my invention;

Fig. 2 is a piece of the improved brim with a piece of the adjacent band and side crown, showing on an enlarged scale the construction.

Fig. 3 is a view of one form of straw-braid used in making a straw-braid hat of any design, with or without my improvement.

Fig. 4 is a piece of straw-braid having both edges pattern edges, in this figure saw-tooth edges; but they may be of any pattern.

40 In the completed hat A, the brim B is shown to be made of six straw braids C stitched together, but it may be made of more or fewer braids, preferably all in one length, spiral, and stitched together, on a sewing machine. D is the side crown; E is the tip, F is the hat band; G is the band row, H is the edge of the brim; I is the right edge of the braid; K is the lap edge.

50 The brim of the hat in the drawing is flat, but it may be curved, rolled or bent up or down.

Straw-braid, the raw material for making such hats has an ornamental edge I, in the drawing shown as a saw-tooth edge, or it may be of fan shape pattern, or like a flat or blunt saw tooth, or of countless other

forms, scores of patterns being in use this year, some of them new, and hundreds of other patterns having come and gone in years past; but the pattern edge in the trade 65 and in this specification is called the right edge and designated I, and is the edge which is exposed on the outside of the hat; K, the other edge of the straw-braid, is called the underlap or inside edge, and this 65 underlap K of the braid is covered by the right edge I of the adjacent braid, and the two are stitched together to make the hat.

I will describe my improved hat by describing the steps in making a flexible brim 70 straw-braid hat, having my improvement, and by describing in outline the sewing machine and its guides on which my improved hat can be most conveniently stitched; but I do this by way of illustration and not as a 75 limitation.

A flexible or soft-brim straw hat is stiffened more or less, preferably two and one-half braids from the edge, with French gelatin glue of $3\frac{1}{2}$ degrees Baumé density; 80 the remaining inner part of the brim and the lower part of the side crown to about an inch above the band-row is stiffened only a little, with the same glue, but of only one-half degree Baumé; the remainder of the 85 side crown and the whole of the tip are stiffened with the same glue of $3\frac{1}{2}$ degrees Baumé density, leaving flexible the part around the head size so that the hat may conform to the head. 90

This is the well-known flexible brim, straw-braid straw hat, but it contains a serious blemish and a weakness which are objectionable to dealers and to those who would otherwise wear them, that is, the 95 braids open when the hat is handled, lifted, domed, or doffed.

This is a matter of construction and of manufacture. Heretofore, in starting from the button, the braid is lapped on top of the 100 button and fed on top throughout the entire process of sewing, to the edge of the brim. Thus, the pattern edge, for example, the saw teeth of Fig. 1, point away from the band and toward the edge of the brim, 105 and each saw-tooth edge of the braid is over the next outer lap edge, going from the band to the edge of the brim. By my improvement, the right edge of the braid points away from the edge of the brim and 110 toward the hat band, and the lap edge of every braid in the brim is under the right

edge, going from the band to the edge of the brim. And my preferred way of making the hat as a whole is to make the crown the old way, from the button to the head-size, in other words, having the right or exposed edge of the straw braid pointing outwardly and down, doing this on the ordinary machine. I then reverse the point and the braid and sew, from the head-size out, with the saw teeth headed toward the band; and to do that it is necessary to feed the braid over instead of under, that is, the braid in the machine is fed over the crown, at the start, and over the sewed part of the hat whereby the right or exposed edge of the braid points toward the band, and I thus get a brim that does not open objectionably, though only slightly stiffened, or even when not stiffened at all.

But to make this improved hat, it is necessary to change the present hand-stitched straw machine for sewing the braid, in which the braid is under the sewed work and on a broad flat plate, both the braid and the work being guided from the right side and the work guided from its outer edge. The change in the machine,

which I introduce is such that the work is guided from the first sewed right edge of the sewed work and the braid fed over instead of under, and still guided from the right edge.

The improved straw hat so made has a flexible brim which when bent down will not open between the braids, or opens very little, and none shows, the brim is the firmer fabric and yet no less flexible, and the head-size readily takes the shape of the head.

There may be considerable variations in this improved hat without departing from the spirit of my invention.

What I claim and desire to secure by Letters Patent is—

In a straw-braid hat, a brim having the right or ornamented edge of the braid directed toward the crown.

In witness whereof I have hereunto set my hand at Norwalk, Connecticut, this 25th day of October, 1915.

PHILIP N. KNAPP.

In presence of—

E. H. Moersomay,

John Cavanagh.
